DESIGN FOR A COMBINED SYRINGE BAG
AND TUBE SUPPORT

Robert O. Ferguson, Bristol, Tenn., assignor of
one-half to Bristol Steel & Iron Works, Inc.,
Bristol, Va.-Tenn., a corporation of Virginia

Application October 30, 1945, Serial No. 123,323

Term of patent 14 years

(Cl. D83—1)

To all whom it may concern:

Be it known that I, Robert O. Ferguson, a citizen of the United States and a resident of Bristol, in the county of Sullivan and State of Tennessee, have invented a new, original, and ornamental Design for Combined Syringe Bag and Tube Support, of which the following is a specification, reference being had to the accompanying drawing, forming part thereof, in which

Figure 1 is a front elevational view of a combined syringe bag and tube support showing my new design, and

Figure 2 a side view thereof.

I claim:

The ornamental design for a combined syringe bag and tube support, as shown.

ROBERT O. FERGUSON.
